UNITED STATES PATENT OFFICE.

MERRITT GALLY, OF NEW YORK, N. Y.

INK-DISTRIBUTING APPARATUS FOR PRINTING-PRESSES.

SPECIFICATION forming part of Letters Patent No. 356,828, dated February 1, 1887.

Application filed July 3, 1886. Serial No. 207,091. (No model.)

To all whom it may concern:

Be it known that I, MERRITT GALLY, residing at New York city, in the county of New York and State of New York, have invented 5 certain new and useful Improvements in Ink-Distributing Apparatus for Printing-Presses, of which the following is a specification, reference being had therein to the accompanying drawings.

10 In the accompanying drawings, Figure 1 is a side view of the ink-distributing apparatus, showing also a part of the supporting framework and the bed of the press, partly sectional, some parts not essential to the description of 15 this invention being omitted. Fig. 2 is an outline side view showing a modified construction of the improved distributing device.

In Fig. 1 three form-inking rollers, 1 2 3, are shown in contact with two distributing-cylinders, C D. Two slideways, c and d, are shown in the frame-work of the press. In these slideways it is customary to place the composition distributing-rollers of the press; and I have usually driven only the cylinder C 25 by means of the positively-moving machinery of the press, depending upon the friction or adhesion of the composition distributing-roller having its bearings in slot d to drive cylinder D and apply the ink to form-roller 1. This 30 construction and arrangement of cylinders and rollers appears to be somewhat defective, from the fact that if the distributing-roller in slide d is not made of extra tough composition and thoroughly seasoned it is liable to tear or to 35 become too soft from heat produced by friction. I obviate this difficulty by the construction shown in the drawings.

Instead of placing the journals of distributor a in the slideway d, and allowing the distributor to touch both cylinders C and D simultaneously, I place roller a in a vibrating frame, e, which is pivoted at x, and allow the roller to touch first one cylinder and then the other, alternately. I produce the movement 45 of frame e by means of the bar f, pivoted to the frame e, as at t, and connect this bar f to or operate it in connection with some regularly-moving part of the press.

In Fig. 1 the bar f is shown as yoked onto 50 the hub of the fountain ductor-roller frame, which has a movement regularly for each en-

tire movement of the press. I connect the bar f with the ductor-frame z, for two reasons: First, it forms a convenient operative attachment having a regularly-occurring movement; 55 and, secondly, it produces the movement of frame e at a time most advantageous in the process of distribution and application of ink.

It will be seen by examination of the drawings that during the time the ductor-roller is 60 taking ink on the fountain-roller s the distribution of the ink previously applied to cylinder C is going on, and thoroughly-distributed ink is applied to the roller a from cylinder C. As the ductor-roller leaves the 65 fountain to apply the additional undistributed ink to cylinder C the roller a leaves cylinder C and is carried by its frame e to cylinder D, from which it does not return to cylinder C until ductor d returns to the fountain-roller s. 70 No ink therefore can reach cylinder D until it has first been thoroughly distributed. The distribution of each fresh application of ink to cylinder C is made while the inking-rollers 1 2 3 are inking the form on the face of the 75 bed at R, so that no undistributed ink can reach the form-inking rollers.

The construction as described allows me to drive both cylinder C and cylinder D by movement of the machinery of the press. Gearing 80 is shown in partial view for both cylinders in Fig. 1.

The movement of bar f is shown in Fig. 1 as produced by means of the cam-wheel E and fountain ratchet-lever F. It may be more directly produced by carrying bar f down to cam-wheel E', having reciprocating motion given to it directly by the cam, as shown in Fig. 2. The bar f may otherwise be connected with lever F by pivoting at v, as shown by 90 the dotted lines. A distributor may occupy the slot c, and other distributors be applied to either or both of the cylinders C D, if desired. These are omitted from the drawings for the purpose of more clearly showing the parts and 95 operation of the present invention.

The roller-frame e may be pivoted directly to the frame-work H, but is shown as pivoted to a slide, y, which is set in position by means of the set-screw l. The slide y is duplicated— 100 one slide for each side of the press. This construction provides for easy application of the

device to presses already in use having the slideways d . The adjustability of the slides y also provides for perfectly lining the roller a as to the distributing-cylinders C D, and also 5 for making allowance in the movement of roller a for shrinkage of its composition.

The form-inking rollers 1 2 3 are shown in the drawings, 1 on cylinder D, and 2 3 on cylinder C. A greater number of cylinders may 10 be used having one or more form-rollers to each. The gist of the invention requires that there be at least two distributing-cylinders, and to each cylinder a form-inking roller or rollers.

15 I claim—

1. The combination, with a plurality of distributing-cylinders in a printing-press, from all of which the form-inking rolls receive their ink supply, of a distributor-roll alternately 20 engaging said cylinders.

2. The combination, in a printing-press, of a plurality of distributing-cylinders, with all of which the form-rolls come in contact for their ink supply, a distributing-roll adjustable relatively to the distributing-cylinders, and mechanism, substantially as described, by which said distributing-roll is brought into contact alternately with the distributing-cylinders.

25 3. In a printing-press in which a plurality of form-inking rolls take their ink separately from a plurality of distributing-cylinders, and in combination therewith, a distributing-roll, as a , and its carrier connected with a movable

part of the press, by which said distributing- 35 roll is brought alternately into contact with the distributing-cylinders at each complete movement of the press.

4. The combination, with the form-inking rolls, as 1 and 2, and the distributing-cylinders C D, which separately supply said inking-rolls, of the roll a , hung in the frame, and a connection therefrom to the ductor-roll frame by which roll a is brought alternately into contact with the rolls C and D, as set forth. 40 45

5. The combination, in a printing-press of the character described, of the distributing-cylinders C and D, both positively driven from the moving parts of the press, of the distributor a , and a connection, substantially as described, to the moving parts of the press, by which roll a is made to engage alternately with the rolls C and D. 50

6. The combination, with the frame having positively-driven distributing-cylinders C D 55 and slot d , of the slide y , adjustable in said slot, the frame e , pivoted thereto, the roller a , supported in said frame, and mechanism, substantially as described, by which frame e and its roll are rocked on the pivots of said frame, 60 as set forth.

In testimony whereof I affix my signature in presence of two witnesses.

MERRITT GALLY.
